UNITED STATES PATENT OFFICE.

HENRY NORMAN LEASK, OF EGREMONT, ENGLAND.

FURNACE.

960,969.

Specification of Letters Patent.

Patented June 7, 1910.

Application filed September 9, 1907. Serial No. 392,003.

To all whom it may concern:

Be it known that I, HENRY NORMAN LEASK, British subject, and resident of Egremont, county of Chester, England, have invented 5 certain new and useful Improvements in Furnaces, of which the following is a specification.

This invention relates to furnaces of the type described in the specification attached 10 to my application for patent filed concurrently with the present application Serial Number 392,004 and in which a furnace constructed with a rising and falling grate is described and has reference to a special construction of furnace built according to the 15 invention described in such concurrent application.

It consists essentially of a furnace in which the whole or part of the sole table or hearth 20 of the fire is constructed in such a manner that it can be raised or lowered as desired and so that, when lowered, it can be dropped on to a truck or carriage to enable the hearth and its charge or contents to be wholly removed from the furnace, and to enable a discharged or a freshly charged grate to be run 25 into position and raised into the furnace. Such a construction permits of very easily and readily charging or discharging or 30 clinkering a furnace of inserting or withdrawing a billet or ingot, or a crucible or the like and of readily transporting same to any desired position, and is applicable to any furnace in which it may be found advantageous to so remove the hearth or a portion thereof.

The invention will be fully described with reference to the accompanying drawings.

Figure 1 is a transverse section through 40 the furnace. Fig. 2 is a section on the line $x-x$, Fig. 1. Fig. 3 is a transverse section through the furnace shown provided with a charging chamber.

The upper part of the furnace or cell A 45 is of any usual construction. The grate or hearth B is supported on a hydraulic or other ram b in such a manner that it can be raised and lowered in the furnace as desired, and is formed of a flat or approximately flat 50 plate P preferably having an upwardly projecting flange p all around it, as shown though it may be of any other desired shape. Co-operating with the grate, which has a bodily vertical movement, are fixed members or 55 hollow boxes Q and b' which constitute side and end air supplying means for the grate

when the latter is elevated, said boxes being suitably secured to the walls of the cell and provided with perforations through which the air supply for the furnace is passed. 60 If desired these boxes may be divided and steam or water as well as air may be passed into the fire.

The hollow boxes surrounding the grate as above noted are practically continuous or 65 provide an air supplying rim with an inner wall sloping downwardly and outwardly, or sloping toward the bottom of the rim or box so that the clinkers will fall away from the rim or box and be carried downwardly with 70 the grate as the latter is lowered.

The ram b for raising and lowering the grate preferably passes through the frame of the truck R and when the grate B rests on the latter the ram is lowered still farther 75 out of the way of the truck. The latter is then moved into the chamber H where the air supply for the furnace may be passed over or through it to extract the heat from any clinker, or other charge thereon it may 80 be desired to cool. This form of grate may with great advantage be applied to refuse destructors as the refuse can be burned thereon continually without the necessity of stopping the furnace to clear the grate of clinker. 85 As the refuse is burned thereon and the clinker is formed the grate is gradually lowered without any interference with the air supply which enters through the end boxes and side boxes b' Q. If desired 90 guides S may be provided to maintain the grate in the proper position, as it is raised or lowered.

In one form of the invention a second in- 95 closed chamber T (see Fig. 3) may be con- structed in front of the lower portion of the furnace in which a new truck and grate either charged or uncharged may be in readiness to push the hot grate and its heated or burned out charge into the chamber H, at the 100 same time taking up a position ready for being raised into the fire.

This invention is specially applicable for furnaces in which billets or ingots of metal are to be heated or in which metal or the 105 like is to be melted or for any other furnace in which it may be advantageous to remove the grate or a portion thereof. Any convenient means other than a hydraulic ram may also be employed for raising the grate 110 into position in the furnace and suitable mechanical means may also be employed if de-

sired to maintain the hearth in the raised position.

It will be evident that the furnace has a combustion chamber provided with a grate which is movable toward and from its operative position by a vertical movement, whereby the advantages hereinbefore set forth can be obtained.

What I claim as my invention and desire 10 to protect by Letters Patent is:—

1. The combination of a furnace having a combustion chamber provided with a grate having a bodily vertical movement for placement and displacement in relation to operative position thereof, a hollow perforated air box having a fixed position in the furnace against which the grate is placed when in normal position, a carriage located below the normal position of the grate to receive the latter when it is lowered, and means located 20 below the carriage and movable upwardly through the latter to engage the grate for placing and displacing the latter.

2. The combination of a furnace having a grate mounted for rising and falling motion, a cooling chamber opening into the lower part of the furnace and outside of the main furnace structure, a carriage movable into and out of said cooling chamber and also 30 under the place occupied by the grate when the latter is in normal position in the furnace, and means for raising and lowering

the grate and permitting said grate to rest on or be elevated from the carriage, said carriage being movable over the means for raising and lowering the grate. 35

3. The combination of a furnace having a combustion chamber provided with a rising and falling grate, a ram to raise and lower the said grate, and a carriage movable to a position over the ram, the ram being adapted to lower a grate onto said carriage or to elevate a grate from off the carriage into operative relation with the combustion chamber. 40

4. The combination of a furnace having a combustion chamber provided with a rising and falling grate, a ram to raise and lower the said grate, a carriage movable to a position over the ram, the ram being adapted to lower the grate onto said carriage or to elevate the grate from off the carriage into operative relation with the combustion chamber, and cooling and charging chambers located at opposite sides of the space in 50 which said ram is located. 55

In witness whereof, I have hereunto signed my name in the presence of two subscribing witnesses.

HENRY NORMAN LEASK.
